ELEVATOR CONTROL SYSTEM

Filed May 19, 1928

UNITED STATES PATENT OFFICE

RAY P. HIGBEE, OF PHILADELPHIA, PENNSYLVANIA, ASSIGNOR TO WESTINGHOUSE ELECTRIC & MANUFACTURING COMPANY, A CORPORATION OF PENNSYLVANIA

ELEVATOR CONTROL SYSTEM

Application filed May 19, 1928. Serial No. 278,947.

The invention relates generally to control systems for motors and more particularly to control systems for motors utilized in connection with elevators, hoists and the like.

5 The object of the invention, generally stated, is to provide a simple and inexpensive control system for constant-potential elevator systems which shall maintain an elevator-operating characteristic closely approximating that of a variable-voltage system.

A more specific object of the invention is to provide a control system for constant-potential elevator systems wherein the effectiveness of the elevator-motor windings is gradually and continuously varied in accordance with the speed of the motor to provide for smooth and rapid acceleration and deceleration of the elevator.

20 Another object of the invention is to provide a two-speed elevator-control system wherein the effectiveness of the high-speed motor winding is gradually and continuously varied to accelerate the elevator to full speed, and the effectiveness of the low-speed winding gradually and continuously varied to decelerate the elevator from high speed to a lower speed, as determined by the low-speed motor winding.

25 A further object of the invention is to provide for starting an elevator motor at reduced voltage and automatically increasing the voltage impressed upon the motor, in a gradual and continuous manner, to obtain smooth and rapid acceleration.

30 Other objects of the invention will become evident from the following description, taken in conjunction with the drawing, in which—

35 Fig. 1 is a diagrammatic view of a two-speed constant-potential elevator-control system arranged in accordance with the present invention, and

40 Fig. 2 is a graphical representation of the elevator speed-time curves of acceleration and deceleration which may be obtained by utilizing the present invention.

45 Referring to Fig. 1 of the drawing, the control system, as shown, is suitable for operating a single elevator. As illustrated,

the elevator system comprises an elevator car C suspended in a hatchway by means of a cable Ca which passes over a drum D to a suitable counterweight Cw, in the usual manner.

55 The elevator drum D may be driven by a motor of any suitable type. However, in this particular embodiment of the invention, a two-speed alternating-current elevator motor EM is provided. As shown, the motor EM is direct-connected to the drum shaft and is provided with a squirrel-cage rotor R and a double stator winding. The stator is wound with two separate windings having different numbers of poles in any desired ratio, for obtaining high and low-speed operation. Hereinafter, the low-speed stator winding will be designated as LSW and the high-speed stator winding as HSW.

60 The elevator motor EM is controlled, in the usual manner, through the agency of a car switch CS on the car C which is disposed to control the operation of the "up" and "down" directional switches designated as 1 and 2, respectively, speed switches 4 and 5 and a transfer switch 6.

65 The elevator motor EM may be supplied with power from any suitable source, and, as shown, a constant-potential source of power, comprising line conductors L1, L2 and L3, is provided.

70 Since it is necessary to vary the voltage supplied to the motor for obtaining desirable accelerating and decelerating operating characteristics of the elevator, a plurality of auto transformers 7, 8 and 9, and 11, 12 and 13 are interposed between the power source and the low-speed and high-speed stator windings, respectively. It will be observed that the transformers are provided with transformer windings 14 to 19, inclusive, which are connected to the stator winding of the elevator motor EM in accordance with the well-known auto-transformer principle.

75 The transformer cores, designated as 21 to 26, inclusive, are also provided with auxiliary windings 27 to 32, inclusive, the purpose of which will be described in detail hereinafter.

It will be observed that the transformer windings are provided with low-voltage taps at points 33 to 38, inclusive, which are connected to each stator winding through conductor leads 41, 42, or 43 for the low-speed connection, and through conductor leads 44, 45 and 46 for the high-speed connection.

In order that a more comprehensive understanding of the invention may be obtained, a detailed description of the operation of the system will now be given.

Under normal conditions, the motor EM is operated on the high speed windings, acceleration to full speed being initiated by movement of the car switch CS directly to the extreme position. If desired, however, the motor EM may be operated on the slow speed winding continuously, acceleration to low speed being initiated by movement of the car switch CS to an intermediate speed position. In the following description, both of the above noted control operations will be described in detail.

Assuming that the elevator car C is at a lower floor and that it is desired to operate the elevator at a slow speed in an up direction, the car switch CS is actuated to the first forward position, thereby bridging the fixed contact fingers 47, 48 and 49 by the movable contact segment 51. In this event, an operating circuit is established for the "up" directional switch 1 which may be traced from the line conductor L1, through conductor 52, contact fingers 47, 48 and 49, bridged by the movable segment 51, conductor 53, operating coil of switch 1 and conductor 54, to the energized conductor 55, which is connected to the line conductor L2. It will be observed that the conductor 55 is one which is common to all of the switch-operating circuits and is energized at all times. Therefore, in the description which will appear hereinafter, it will be referred to always as the energized conductor 55.

At this time, an operating circuit is also established for the speed switch 5 which extends from the line conductor L1, through conductor 52, fixed contact members 47 and 48, bridged by the segment 51, conductors 56 and 57, the normally closed contact members 58 of the transfer switch 6, conductor 59, and operating coil of the switch 5, to the energized conductor 55.

Upon the closure of the "up" directional switch 1 and the speed switch 5, an energizing circuit for the low-speed winding LSW of the elevator motor EM is established. The first phase of the three-phase circuit thus established extends from the line conductor L1, through conductor 61, contact member *a* of the "up" direction switch 1, conductors 62 and 63, contact member *a* of the speed switch 5, winding 15 of transformer 8, tap 34, and conductor 42 to one phase winding

of the low-speed stator winding LSW. A second phase extends from the line conductor L2, through conductors 55, 64, and 65, contact members *b* of the speed switch 5, winding 14 of the transformer 7, tap 33, 70 and conductor 43 to a second phase of the low-speed stator winding LSW; and the third-phase circuit extends from the line conductor L3, through conductor 66, contact members *b* of the "up" directional switch 1, 75 conductors 67 and 68, winding 16 of transformer 9, tap 35 and conductors 41, to a third-phase winding of the low-speed stator winding LSW, thus completing the three-phase energizing circuit for the low-speed 80 connection.

It will be observed that the opposite ends of the transformer windings 14, 15 and 16 are disposed to be connected at a common point by means of the switch 71, through 85 the conductors 72, 73 and 74, which causes the transformers 7, 8 and 9 to provide a low voltage by reason of the tap connections at points 33, 34 and 35 on the respective windings. However, in this instance, the switch 71 is in the open position, and, therefore, the transformer windings 14, 15 and 16 are not connected at the common point and function merely as reactor coils in circuit with the motor windings. 90

In order to control the effect of the reactor coils upon the voltage applied to the motor windings, a direct-current generator 75 is utilized for exciting the auxiliary windings 27, 28 and 29 of the transformers 7, 8 100 and 9, and also the auxiliary windings 30, 31 and 32 of the transformers 11, 12 and 13. It will be understood that, by varying the magnetization of the transformer cores, the effect of the reactor coils will be varied in such 105 manner as to cause a greater or lesser voltage drop across them and thereby vary the voltage impressed upon the motor windings. When a low degree of magnetization is maintained in the cores, the effect of the reactor coils is a maximum, and, therefore, the voltage applied to the motor windings is a minimum, and, by gradually increasing the magnetization of the cores from a minimum to a maximum degree, the effect of the reactor 110 coils is gradually and continuously reduced to a minimum, and the voltage applied to the motor windings is a maximum. 115

In order to control the magnetization of the cores in this manner, the direct-current generator 75 is disposed to be driven by the elevator motor EM. However, in this instance, in order to simplify the drawing, the two machines have been shown separately although it is to be understood that, in operation, they are to be connected together in any suitable manner. 120

It will be observed that, upon closure of the directional switch 1 and speed switch 5, an energizing circuit for the transformer 125

auxiliary windings was established which may be traced from one terminal of the armature 76 of the generator 75, through conductors 77 and 78, auxiliary coils 29, 28 and 27, conductor 79, contact member *c* of the speed switch 5, conductors 81, 82 and 83, contact member *c* of the "up" direction switch 1 and the field winding 84 of the generator 75, to the opposite terminal of the armature 76. Since the speed of the generator 75 varies in accordance with the increasing speed of the elevator motor EM, the generated voltage also increases in direct proportion. The magnetization of the former cores, therefore, may be so controlled as to gradually decrease the effect of the reactor coils comprising the transformer windings 14, 15 and 16 until a point of maximum magnetic saturation is reached in which case the effect of the reactor coils is reduced to any desired extent.

As will be more fully described herein-after, in connection with the control operations involved in decelerating the motor EM, it is desirable that, when motor EM is running at the speed determined by the low speed windings, the cores 21, 22 and 23 will be substantially unsaturated, so that the voltage drop across the windings 14, 15 and 16 will be substantially a maximum. For reasons which will be more apparent when discussed in connection with the decelerating operations, it is also desirable that the interphase connections of the transformers 7, 8 and 9 remain interrupted by the contact members of relay 71 except at such times as the motor is decelerating from the speed determined by the high speed windings to a speed somewhat in excess of the speed determined by the low speed windings. The cores 21, 22 and 23 are, therefore, so designed as to be unsaturated by a voltage value for generator 75 which corresponds to the low speed of the elevator motor EM. Similarly, the coil of relay 103 is so designed as to be ineffective to complete the circuit of relay 71 at a voltage of generator 75 which corresponds to a low speed of the motor EM.

If the car switch CS is operated to the low speed position, therefore, the interphase connections of transformers 7, 8 and 9 remain open, windings 14, 15 and 16 function as reactors, the voltage drops across which do not appreciably vary as the speed of motor EM increases, by reason of the unsaturated condition of cores 21, 22 and 23.

To bring the elevator car to rest from low speed, the car switch CS is returned to the neutral and illustrated position, thus deenergizing the direction and speed switches 1 and 5. The system may be brought finally to rest under the influence of the usual magnetic brake (not shown).

As stated, the elevator may also be started and accelerated on the high-speed wind-

ing HSW by operating the car switch CS directly to the full forward position. In this case, the low-speed winding is momentarily connected, as hereinbefore described, but, since the transfer to the high-speed winding takes place immediately, it has very little effect.

When the car switch CS is in the full forward position, an additional contact finger 50 is bridged by the movable segment 51 to establish an operating circuit for the transfer switch 6, which may be traced from the line conductor L1, through conductor 52, contact fingers 47 and 49, bridged by the segment 51, conductor 85 and operating coil of the transfer switch 6; to the energized conductor 55. Upon the operation of the transfer switch 6, the normally closed contact members 58 are opened to deenergize the operating circuit of the speed switch 5, and the normally open contact members 85 are closed to establish an operating circuit for the speed switch 4, which may be traced from the line conductor L1 to contact members 47 and 48, bridged by the segment 51, conductors 56 and 57, contact members 86, conductor 87 and operating coil of the speed switch 4, to the energized conductor 55.

Upon the closure of the speed switch 4, an energizing circuit for the high-speed winding HSW is established, one phase of which may be traced from the energized conductor 55, through conductors 64 and 88, contact members *b* of the switch 4, winding 19 of the transformer 13, tap 38, and conductor 44, to one phase of the high-speed stator winding HSW. Since the "up" direction switch 1 is closed, conductor 62 is energized, and, therefore, a second-phase circuit extends from conductor 62, through contact members *a* of the switch 4, winding 18 of the transformer 12, tap 37, and conductor 45, to a second phase of the high-speed stator winding. Likewise, the third-phase circuit extends from the energized conductor 68, through the winding 17 of the transformer 11, and conductor 46 to a third phase of the high-speed stator winding.

In order to provide a low initial voltage for starting or accelerating on the high-speed winding, a normally closed switch 89 is utilized to connect the opposite ends of the transformer windings 17, 18 and 19 to a common point through conductors 91, 92 and 93. In order to provide for increasing the voltage of the transformer connection thus established to accelerate the motor EM on the high-speed winding HSW, the speed switch 4 is provided with a dash-pot-controlled switch 94 for controlling the operation of the transformer connecting switch 89. As shown, the armature of the switch 94 is connected to the movable member of the switch 4 by means of a coil spring 95 which, as will be readily understood, permits the closure of switch 4

and permits the closure of the switch 94 to be retarded by the operation of the dash-pot 96. Since the timing of the dash-pot operation may be readily regulated in any well-known manner, the time at which the transformer connection, as made by the switch 89, is interrupted may be varied as desired.

Upon the closure of the switch 94, after a predetermined time interval subsequent to the operation of the speed switch 4, an operating circuit is established for the switch 89 which extends from the energized conductor 55, through contact members *d* of the switch 94, operating coil of switch 89 and conductor 61, to the line conductor L. The switch 89, therefore, is actuated to its open position, which opens the transformer connection. Consequently, the transformer windings 17, 18 and 19 remain connected in series with the high-speed stator windings HSW to serve as reactor coils, as described hereinbefore in connected with the acceleration on the low-speed connection.

It will be observed that the direct-current exciting circuit for the auxiliary coils 30, 31 and 32 was established upon the closure of the speed switch 4 during the transfer from the low-speed to high-speed winding. As shown, this energizing circuit now extends from one terminal of the armature 76 of the generator 75, through conductors 77 and 78, auxiliary coils 30, 31 and 32, conductor 97, contact members *c* of the switch 4, conductor 82, contact members *c* of the directional switch 1 and field winding 84, to the opposite terminal of the armature 76. Since the voltage generated by the generator 75 is now built up to a predetermined value, depending upon the operating speed of the motor EM, when connected to the transformer taps 36, 37 and 38, it will be readily understood that the design of the auxiliary windings 30, 31 and 32 should be such as to cause a minimum magnetization of the transformer cores 24, 25 and 26, and thereby obtain a maximum effect of the reactor coils when the motor speed is low.

As described hereinbefore, the excitation of the auxiliary windings 30, 31 and 32 is gradually and continuously increased in response to the increase in speed of the elevator motor EM to a degree where a maximum magnetic saturation of the transformer cores is obtained. In this event, the effect of the reactor coils 17, 18 and 19 is decreased to a minimum, and, therefore, approximately full line voltage is applied to the motor windings. However, in order to supply full voltage to the elevator motor EM, provision is made for short-circuiting the reactor windings at this time. For this purpose, a switch 98 is utilized, and, as shown, is provided with contact members *a*, *b* and *c*, each of which is connected to short-circuit the reactor coils upon the closure of the switch 98 and there-

by connect the motor EM directly to the line conductors L1, L2 and L3 through the directional switch 1 and speed switch 4.

In order to control the operation of the short-circuiting switch 98, a relay 99 is provided and disposed to be energized by the direct-current generator 75. As shown, the operating circuit for the relay 99 extends from the generator 75, through conductors 77 and 101, operating coil of relay 99, conductors 102, and 83, contact member *c* of the "up" direction switch 1 and field winding 84, to the opposite terminal of the armature 76. As will be readily understood, the operation of the relay 99 may be made to occur in response to any predetermined voltage of the generator 75, and, in this instance, it is set to operate when the speed of the motor EM increases to approximately its maximum speed, with the reactors in the circuit. Upon the closure of the relay 99, the operating circuit for the short-circuiting switch 98 is established to extend from the energized conductor 55, through contact members of relay 99, operating coil of short-circuiting switch 98, to the conductor 63 which is now energized.

Referring now to Fig. 2, the acceleration of the elevator motor EM is shown diagrammatically by the curve designated as X. As will be observed, the curve X shows the speed of the elevator at any instant from the time of starting to the point of maximum speed in respect to the total time required to reach the maximum speed. At point A on the curve, an initial low voltage from the transformer windings connected as auto-transformers is applied to the high-speed stator windings, and the motor accelerates along the curve, as shown, to point B. At this time, the short-circuiting switch 89 opens to connect the transformer windings 17, 18 and 19 in the motor circuit to operate as reactors, and acceleration of the motor EM is continued at a higher rate to point C with increasing magnetization of the transformer cores, where, in response to the speed of the motor, the switch 98 is operated to short-circuit the reactor coils, and the acceleration continues, at a lesser rate, to the point of maximum speed at D.

In reducing the speed of the car preparatory to bringing the elevator to a stop, a sequence of operations occurs which are as follows: the car switch CS is returned to the first forward position, thereby unbridging the contact member 50 which permits the transfer relay 6 to drop out and deenergize the operating coil of the speed switch 4 and, at the same time, establish an energizing circuit for the speed switch 5 through its contact members 58, as described in detail hereinbefore. As will be readily understood, this operation reconnects the motor on the low-

speed winding while running at a speed determined by the high-speed winding.

In accordance with a well-known principle of the regenerative braking action of an induction motor, when running at a speed in excess of its normal speed, a certain amount of braking torque will be obtained which will depend, for its magnitude, upon the value of voltage impressed upon the low-speed winding at the time of transfer. In order to reduce the braking force to a minimum to obtain a smooth deceleration and eliminate any possibility of a bump occurring at the beginning of the deceleration period, it is necessary to make the initial applied voltage relatively low. In order to accomplish this purpose, the connecting switch 71 for the transformer windings 14, 15 and 16 is controlled in such manner as to connect the transformer windings 14, 15 and 16 to provide a reduced voltage at the time of transfer.

In this instance, the operation of the switch 71 is controlled by a relay 103 which is similar to the relay 99 and is disposed to be operated in response to the development of a voltage by the generator 75. As shown, the operating coil of the relay 103 is connected for energization from conductor 77, through conductor 104, operating coil of relay 103, conductors 105 and 83, through contact member *c* of the direction switch 1 and field winding 84, to the opposite terminal of the generator 75. Since the relay 103 may be set to operate at any predetermined voltage value, its operation may be so timed as to permit the connecting switch 71 to drop out and thereby connect the reactor coils comprising the transformer coils 14, 15 and 16 in the motor circuit in response to any predetermined reduction in the speed of the motor EM after transferring from the high-speed to the low-speed winding.

At the beginning of the deceleration period, with the reactor coils 14, 15 and 16, connected in the motor circuit the voltage developed by the generator 75 is a maximum, causing the reactor cores 21, 22 and 23 to be highly magnetized and, therefore, the effect of the reactor coils upon the applied voltage is a minimum. Therefore, an appreciable increase in the voltage impressed upon the low-speed windings LSW occurs which increases the regenerative-braking action and thereby increases the rate of deceleration. As the speed of the motor EM decreases, the effectiveness of the reactors increases, since the magnetic saturation of the cores decreases, and, therefore, the motor is gradually and continuously decelerated to a speed determined by its low-speed winding operating with the reactors comprising transformer windings 14, 15 and 16 in the circuit. At this point, further deceleration is attained by returning the car switch to the "off" position, which disconnects the elevator motor EM

from the power source and simultaneously applies a mechanical brake (not shown) in the usual manner.

In order to more clearly describe the deceleration action, reference may be had to Fig. 2 and to the curve designated as Y. As will be observed, the point A' on the curve designates the maximum operating speed of the elevator and it is at this point that the transfer occurs from the high-speed winding to the low-speed winding upon the return of the car switch CS to the first "forward" position. The elevator then decelerates to a point B' while connected to the low-voltage taps 33, 34 and 35 of the transformer, the rate of deceleration being comparatively low. At the point B', the reactor circuit is established by the operation of the relay 103, as described hereinbefore and the voltage applied to the winding LSW is increased to substantially a maximum value, by reason of the fact that the cores 21, 22 and 23 are highly saturated, and the reactance of windings 14, 15 and 16 is correspondingly low. The rate of deceleration increases perceptibly at this point by reason of the increased braking torque exerted by the motor. As the speed falls, however, the magnetization of the cores 21, 22 and 23 is proportionately decreased, which gradually increases the reactance of windings 14, 15 and 16, and consequently decreases the braking torque exerted by the motor. The variation in braking torque causes the rate of deceleration of decrease gradually between the points B' and C'. The point C' represents the operating speed of the motor as determined by the low speed windings with the reactive effect of windings 21, 22 and 23 at a maximum value. Further deceleration is obtained to the point D', which is zero speed, by application of the brake, as hereinbefore described.

Thus, it will be apparent that a relatively simple and inexpensive control system has been provided wherein an inexpensive squirrel-cage induction motor may be utilized for operating an elevator, and operating characteristics obtained which are substantially the same as those obtained by a more expensive variable-voltage system of control. Furthermore, by utilizing the reactor principle of operation, the acceleration and deceleration of the elevator is automatically obtained in such manner as to obtain the most desirable rate of speed change in either the upward or the downward operation of the elevator, with a noticeable elimination of bumps, such as would occur if resistor control of the motor should be employed.

The described embodiment of my invention being merely illustrative, I do not desire to be limited to the exact details of the apparatus disclosed except as they are defined in the appended claims.

I claim as my invention:

1. In a motor control system, in combination, a motor having dual primary windings for obtaining two-speed operation, a source of power for the motor, and means for controlling the speed of the motor comprising means interposed between the primary windings of the motor and the source of power for varying the voltage applied to either primary winding, said means including variable impedance means and means for reconnecting said variable impedance means as transformers, said voltage varying means being operable in response to the speed of said motor.
2. In a motor control system, in combination, a motor having high and low-speed windings, a source of power for the motor, means for connecting the motor windings to the power source, means interposed between the motor and power source for controlling the voltage impressed upon the windings, said means comprising auto-transformers with means for interrupting the interphase connections thereof, said autotransformers having auxiliary windings on the core thereof and means for exciting said auxiliary windings in accordance with the speed of the motor to continuously vary the magnetization of the core and thereby vary the voltage drop across the transformer windings.
3. In a motor control system, in combination, a motor having high and low-speed primary windings, a source of constant-potential power for the motor, directional and speed switches for connecting the motor to the power source, means interposed between the primary windings of the motor and the power source for varying the primary voltage during acceleration and deceleration of the motor, said means comprising auto-transformers provided with main transformer windings and auxiliary windings inductively related thereto, means operable in response to the closure of the high-speed switch for causing said auto-transformer windings to function as reactors to accelerate the motor, and means responsive to the speed of the motor for varying the excitation of the auxiliary windings to change the reactance in the circuit and thereby vary the voltage applied to the stator winding.
4. In a motor-control system, in combination, a motor, a source of power for the motor, means for connecting the motor to the source of power, voltage-varying means interposed between the motor and the power source, said means comprising auto-transformers having interphase connections, and provided with main and auxiliary windings, means to interrupt the interphase connections of said transformers, and means responsive to the speed of the motor for controlling the effect of the transformer main windings, said means being disposed to vary the excitation of the auxiliary windings to gradually and continuously vary the effect of the main transformer windings to control the voltage impressed upon the motor.
5. In an alternating-current motor control system, a motor having windings, circuits including said windings, a source of power for said motor, starting mechanism for connecting said motor to said source, and means for controlling the acceleration of said motor comprising additional windings, means comprising time-controlled means for connecting said additional windings in said circuits as transformers, and for thereafter reconnecting said additional windings in said circuits as reactors, and means responsive to the speed of said motor for gradually reducing the effect of said additional windings.
6. In an alternating-current motor control system, a motor comprising primary windings, a source of voltage for said motor, circuit connections between said source and said windings including starting switches, and means to control the acceleration of said motor comprising additional windings, means adapted to connect said additional windings in said circuits as transformers to provide a reduced starting voltage for said motor and responsive to the operation of said starting switches to reconnect said additional windings in said circuits as reactors, and means controlled by the speed of said motor for decreasing the effect of said additional windings to thereby gradually increase the voltage supplied to said motor.
7. In an alternating-current motor control system, a motor comprising primary windings, a source of voltage for said motor, circuit connections between said source and said windings including starting switches, and means to control the acceleration of said motor comprising additional windings normally interposed in such circuits, means adapted to connect said additional windings as transformers to provide a reduced starting voltage for said motor, said last named means being rendered effective by operation of said starting switches to reconnect said additional windings in said circuits as reactors, magnetizable cores associated with said additional windings, means responsive to the speed of said motor for saturating said cores to thereby reduce the effect of said additional windings, and additional means responsive to a predetermined speed of said motor for excluding said additional windings from said circuits.
8. In an alternating-current motor control system, a motor having primary windings, a source of voltage for said motor, circuit connections between said source and said windings including starting switches, and means to control the acceleration of said motor comprising additional windings normally interposed in said circuits, time-con-

trolled means adapted to connect said additional windings in said circuits as transformers to provide a reduced starting voltage for said motor and to thereafter interrupt said 5 transformer connections and render said additional windings effective as reactors, means responsive to the speed of said motor for gradually decreasing the effect of said additional windings, and means responsive to 10 a predetermined speed of said motor for excluding said additional windings from said circuits.

9. In a motor control system, in combination, a motor having high and low-speed primary windings, a source of power for the motor, circuit connections between said motor and said source, and means for gradually decelerating from high speed to low speed, including means for transferring the power 20 connections from the high speed winding to the low speed windings, variable impedance means for gradually varying the effectiveness of the low-speed winding, and means for reconnecting said variable impedance means 25 as transformers.

10. In a motor control system, in combination, a motor, said motor having high and low-speed primary windings, a source of power for the motor, means for transferring the power connection from the high-speed winding to the low-speed winding, means for rendering said low-speed winding relatively ineffective immediately following the transfer to obtain a low value of regenerative-braking force, said means being responsive 30 to the speed of the motor, and for increasing the effectiveness of said low-speed winding in response to a predetermined reduction in motor speed during the initial portion of 35 the deceleration period, and means for gradually and continuously decreasing the effectiveness of the low-speed winding during the latter portion of the deceleration period to 40 reduce the motor speed to a value substantially the same as the synchronous speed of the low-speed winding.

11. In an alternating-current motor control system, a motor having a winding, a source of power for said motor, switching mechanism operable to cause said motor to decelerate between predetermined speed limits, and means associated with said winding to control the rate of change of speed of said motor comprising means, responsive to operation of 45 said switching mechanism, effective to establish an initial low value of braking torque and to thereafter increase said value of braking torque, and additional means rendered effective after said increase to thereafter gradually reduce the value of said braking torque.

12. In a motor control system, in combination, a motor having high and low-speed primary windings, a source of constant-potential power for the motor, directional and speed switches for connecting the motor to

the power source, means interposed between the primary windings of the motor and the power source for varying the primary voltage during acceleration and deceleration of the motor, said means comprising auto-transformers provided with main transformer windings and auxiliary windings inductively related thereto, means for accelerating the motor to full speed on the high-speed primary winding, means responsive to the speed 75 of the motor for connecting the main windings of the auto-transformers in the low-speed primary circuit to operate as auto-transformers, said means being disposed to connect said windings as reactors at a predetermined speed after changing from the high-speed connection to the low-speed connection, and means responsive to the motor speed for varying the excitation of the auxiliary windings to gradually increase the reactance value 85 of the reactors, thereby providing smooth deceleration of the elevator from maximum to minimum speed.

13. In an alternating-current motor-control system, a motor having primary winding 90 connections for low and high speed operation of said motor, a source of voltage for said windings, circuit connections between said source and said windings, and selective switching means to control the speed of said 95 motor, means rendered effective by the operation of said switching means to cause deceleration of said motor from high speed to low speed to reduce the voltage supplied to said low speed winding connections, including 100 means for thereafter increasing said voltage, and means operably responsive to the operation of said voltage increasing means for thereafter gradually decreasing said voltage.

14. In an alternating-current motor control system, a motor having primary winding connections for low and high speed operation, a source of voltage for said motor, selective switches to control the speed of said motor, and means responsive to operation of 105 said selective switches to cause said motor to decelerate from high speed to low speed for controlling the rate of change of speed of said motor, said rate-controlling means comprising additional windings, and means disposed to connect said additional windings as 110 transformers in said low speed winding connections to thereby supply an initial reduced voltage to said motor, said means being effective to thereafter interrupt said transformer connections to thereby increase the voltage applied to said motor.

15. In an alternating-current motor control system, a motor having primary winding 115 connections for low and high speed operation, a source of voltage for said motor, selective switches to control the speed of said motor, and means responsive to operation of said selective switches to cause said motor to 120 decelerate from high speed to low speed for 125 130

controlling the rate of change of speed of said motor, said rate-controlling means comprising additional windings, means disposed to connect said additional windings as transformers in said low speed winding connections to thereby supply an initial reduced voltage to said motor, said means being effective to thereafter interrupt said transformer connections to thereby increase the voltage applied to said motor, and means responsive to the speed of said motor for controlling said interrupting means.

16. In an alternating-current motor control system, a motor having primary winding connections for low and high speed operation, a source of voltage for said motor, selective switches to control the speed of said motor, and means responsive to operation of said selective switches to cause said motor to decelerate from high speed to low speed for controlling the rate of change of speed of said motor, said rate-controlling means comprising additional windings, means disposed to connect said additional windings as transformers in said low speed winding connections to thereby supply an initial reduced voltage to said motor, and to thereafter render said additional windings effective as reactors and increase the voltage applied to said motor, and means for gradually increasing the effect of said additional windings to thereby reduce the voltage applied to said motor.

17. In an alternating-current motor control system, a motor having primary winding connections for low and high speed operation, a source of voltage for said motor, circuit connections between said source and said windings, selective switches to control the speed of said motor, means responsive to operation of said selective switches to cause said motor to decelerate from high speed to low speed for controlling the rate of change of speed of said motor, said rate-controlling means comprising additional windings, means disposed to connect said additional windings as transformers in said low speed winding connections to thereby supply an initial reduced voltage to said motor, and to thereafter render said additional windings effective as reactors and increase the voltage applied to said motor, means for thereafter gradually increasing the effect of said additional windings to thereby reduce the voltage applied to said motor, and means responsive to the speed of said motor for controlling said rate-controlling means.

18. In an alternating-current motor-control system, a motor having primary winding connections for low and high speed operation of said motor, a source of voltage for said motor, circuit connections between said source and said windings, selective switches to control the speed of said motor, and means responsive to operation of said selective switches to cause said motor to decelerate

from high speed to low speed for controlling the rate of change of speed of said motor comprising means to reduce the voltage initially supplied to said low speed winding connections, means responsive to a predetermined speed of said motor for increasing said voltage, and means responsive to the speed of said motor for thereafter gradually decreasing said voltage.

In testimony whereof, I have hereunto subscribed my name this 12th day of May 1928.

RAY P. HIGBEE.
